Primary Examiner — John R Yeh(57) **CLAIM**

The ornamental design for a garment folding apparatus, as shown and described.

DESCRIPTION

FIG. 1 is a rear elevational view of a garment folding apparatus showing my new design consisting of four components;

FIG. 2 is a front elevational view thereof;

FIG. 3 is a left side view thereof;

FIG. 4 is a right side view thereof;

FIG. 5 is a top plan view thereof;

FIG. 6 is a bottom plan view thereof;

FIG. 7 is a perspective view thereof;

FIG. 8 is a perspective view showing an assembled state of two of the components;

FIG. 9 is a another perspective view showing an assembled state of two of the components;

FIG. 10 shows the perspective view shown in FIG. 9 in an alternative state; and

FIG. 11 is a yet another perspective view showing an assembled state of two of the components;

FIG. 12 is an enlarged view of the portion 12 shown in FIG. 1; and,

FIG. 13 is an enlarged view of portion 13 shown in FIG. 1. The broken lines shown depict portions of the garment folding apparatus that form no part of the claimed design.
